(57) CLAIM

I claim the ornamental design for a baseball bat, as shown and described.

DESCRIPTION

FIG. 1 is a perspective view of the baseball bat embodying the design of the present invention.

FIG. 2 is a front elevational view thereof, the rear being identical to the front.

FIG. 3 is a top plan view thereof, the bottom being identical to the top shown in FIG. 3.

FIG. 4 is a left side elevational view thereof; and,

FIG. 5 is a right side elevational view thereof.

The figures have been shaded to indicate colors.
